L. BUSHA

STRIP SHINGLE

Filed March 17, 1923

FIG. 2

FIG. 3

FIG. 1

Inventor
LEON BUSHA

By Paul, Paul & Moore
ATTORNEYS

UNITED STATES PATENT OFFICE.

LEON BUSHA, OF MINNEAPOLIS, MINNESOTA.

STRIP SHINGLE.

Application filed March 17, 1923. Serial No. 625,847.

To all whom it may concern:

Be it known that I, LEON BUSHA, citizen of the United States, resident of Minneapolis, in the county of Hennepin and State of Minnesota, have invented certain new and useful Improvements in Strip Shingles, of which the following is a specification.

This invention relates to improvements in strip shingles for covering the roofs or walls of buildings formed preferably of roofing felt or material of a similar nature, with a mineral covering or surface usually formed of finely divided slate or similar material.

The object of my present invention is to provide a strip shingle that can be cut from a rectangular sheet or strip of material with practically no waste whatever; that can be conveniently formed either lengthwise or crosswise of the piece of material; that will, when laid, simulate the appearance of a tile or shingle roof, and that will provide at least two thicknesses of shingles at all portions of the roof or wall.

The invention consists generally in the constructions and combinations hereinafter described and particularly pointed out in the claims.

In the accompanying drawings,

Figure 1 is a plan view of a single shingle embodying my invention;

Figure 2 is a plan of a sheet of material or a portion of a sheet, illustrating the manner in which the strip shingles may be cut therefrom;

Figure 3 is a plan view showing a preferred, manner of laying the shingles to form a roof or wall covering.

In the drawing, 1 represents the body portion of the strip shingle, which may be formed, in the usual way, with a foundation sheet of wool felt, a coating or layer of pitch, asphalt or the like, on one surface of the felt, and a layer of crushed slate or similar material pressed into the coating and held in place thereby.

I form, at one edge of the body projecting extensions or butts, 2, 2, here shown of generally rectangular form, but with the base of the butt widened by the diagonal or inclined lines *a*—*b* and the tip of the butt correspondingly narrowed by the inclined or diagonal line *c*—*d*. Separating spaces 3, 3, are thereby provided, each equal in outline or contour and area, to the outline, contour and area of each of the butts 2. The shingle may be cut from a rectangular sheet

of single width by separating said sheet longitudinally on the dotted lines 5, 5, Figure 2, and transversely on the dotted lines 6, 6, and 8, 8.

If the sheet is of double width it will also be severed along the straight dotted line 7, 7. From a single width sheet two strip shingles will be formed by cutting in the manner described and from a double width sheet four such shingles will be formed.

In the starting of the manufacture of the shingles from a double strip, as indicated in Figure 2, there will be at the end of the strip a slight amount of waste as shown between the points marked *e*—*e* at the right in Figure 2 of the drawings, but there will be no further waste until the opposite end of the sheet is reached.

It will be seen that in cutting two of the shingles from a strip wide enough to produce the shingles in pairs, or wide enough to produce four shingles across the sheet, as illustrated in Figure 2, the line 6, 6, extends from the straight edge of the shingle to one of the points *d*, at the end of the butt, while the line 8, 8, extends also from the straight edge of the complementary shingle to the next point *d* on the oppositely extending butt of the next shingle. This arrangement forms a small notch at one side of the end butt, slightly off-setting the line *b*, *c*, at the side of the butt next to the end of the shingle.

The shingles are adapted to be laid as indicated in Figure 3 of the drawings and when so laid they form a roof of quite a different design from the roof shown, for example, in my application 618283 and in some respects a more stable roof than a roof formed by the shingle of that application, for example, the inclined edges *a*, *b*, render the butts 2 wider at the line where they join the main body of the shingle than the butts of my other application and, therefore, these butts will offer greater resistance to being turned up by the wind. In effect what has been done in the present application is to transfer the corner formed by cutting the lines *c*—*d* from the lower edge of the butt to the corner *a*—*b* where the body joins the main butt of the shingle and this transfer materially makes the butt stiffer, although the shingle as a whole is made out of the same amount of material as the shingle of my said other application.

The other minor advantages accompany-

ing the particular form of this shingle for example, while it takes more knives to cut the edges of the shingle in the present application the knives are made smaller on the cutting machine but the strain on each knife becomes less and the cutting edges last longer.

These shingles are preferably cut lengthwise of the sheet as indicated in Figure 2. 5
10 By thus cutting the shingles and making the butts three and one-half inches long and the distance from the ends of the butts to the opposite edge of the shingle ten and three-fourths inches, four strip shingles can 15 be cut, in the manner indicated in Figure 2, from a sheet thirty-six inches wide.

I prefer to construct the shingles so that from the tip of the butt to the other edge or top of the body shall be a distance equal 20 to more than three times the length that the butt projects from the main body of the shingle.

By this arrangement the roof, or covering when laid, as indicated in Figure 3 of the 25 drawings, has three thicknesses of material at the projecting butts, and two thicknesses of material elsewhere.

By this means I produce, with practically 30 no waste a very superior shingle that gives a maximum of three thicknesses of material in the roof or covering (at the butts) and a minimum of two thicknesses of such material elsewhere, and in which the joints are all covered by the butts so that there are three 35 thicknesses of material at each joint, an integral portion of a sheet being over and under each joint.

The length and width of the strip shingles, and the length and width of the 40 butt, may be varied without departing from my invention.

I do not limit myself, therefore to any

particular size or dimension of parts, nor to any particular material for forming the same.

45

I claim as my invention.

1. A strip shingle comprising a body portion having a plurality of separated butts projecting from one edge thereof, the butts being connected with the body portion, at 50 their bases, by inclined lines, and the size and contour of each butt corresponding to the size and contour of the adjoining separating space, whereby a pair of strip shingles may be cut from a rectangular sheet 55 of material, the end of the inclined line at the base of one butt meeting the end line of the body portion at that end of the shingle.

2. A strip shingle comprising a body portion having a plurality of separated butts 60 projecting from one edge thereof, the butts being connected with the body portion at their bases by inclined lines, and the ends of the butts being correspondingly shaped, whereby a pair of strip shingles may be 65 cut from a rectangular sheet of material, the end of the inclined line at the base of one butt meeting the end line of the body portion at that end of the shingle.

3. A strip shingle comprising a body portion having a plurality of separated butts projecting from one edge thereof, the butts being connected with the body portion at their bases by an inclined line, and the ends of the butts being correspondingly 75 shaped, the size and contour of each butt corresponding to the size and contour of the adjoining separating space, the end of the inclined line at the base of one butt meeting the end line of the body portion 80 at that end of the shingle.

In witness whereof, I have hereunto set my hand this 13th day of March 1923.

LEON BUSH.
